UNITED STATES PATENT OFFICE.

GEORGE S. PORTER, OF JACKSON, MICHIGAN.

METHOD OF MAKING WHEELS.

1,367,092.

Specification of Letters Patent.

Patented Feb. 1, 1921.

Application filed February 24, 1919. Serial No. 278,615.

To all whom it may concern:

Be it known that I, GEORGE STANLEY PORTER, a citizen of the United States, residing at the city and county of Jackson, 5 State of Michigan, have invented certain new and useful Improvements in Methods of Making Wheels, of which the following is a specification.

This invention relates to an improved 10 method of making wheels.

My improved method of making wheels is especially adapted for use in the manufacture of vehicle wheels although desirable for use in the manufacture of other types 15 of wheels, pulleys and the like.

The main objects of this invention are:

First, to provide an improved method of 20 making wheels by means of which combination wood and metal wheels may be rapidly and economically manufactured.

Second, to provide an improved method of 25 making wheels which results in wheels of accurate and uniform size and of great strength and durability.

25 Further objects, and objects relating to structural details, will definitely appear from the detailed description to follow.

I accomplish the objects of my invention by the devices and means described in the 30 following specification. The invention is clearly defined and pointed out in the claims.

A structure which is a preferred embodiment of my invention is clearly illustrated 35 in the accompanying drawing, forming a part of this specification, in which:

Figure I is a side view of a wheel manufactured according to my improved method before the hub is applied.

40 Fig. II is a detail sectional view on a line corresponding to line 2—2 of Fig. I, the position of one of the outer felly member flanges prior to its being rolled down being indicated by dotted lines.

45 Fig. III is a view of the split inner felly member showing the lateral distortion thereof to permit rapid assembling of the spokes therein.

Fig. IV is an enlarged detail section on 50 a line corresponding to line 4—4 of Fig. III.

Fig. V is a view similar to Fig. III showing the spokes partially assembled in the split inner rim member.

Fig. VI is a side view of the outer rim 55 member.

Fig. VII is a detail perspective view illustrating the upsetting and sizing of the assembled spokes and rim members.

In the drawing similar reference characters refer to similar parts throughout the 60 several views, and the sectional views are taken looking in the direction of the little arrows at the ends of the section lines.

In carrying out or practising my improved method of making wheels a set of 65 wood spokes 1 having complementary inwardly tapered inner ends 2 and tenoned outer ends 3 are arranged in the split inner metal felly member 4. This felly member is channel-shaped in cross section facing outwardly and has undercut or beveled ends 70 5, its ends being also cut at an angle to the radial plane of the rim. This inner felly member is preferably spirally distorted, as indicated in Figs. III and V, to facilitate 75 the assembling of the parts therein. The spokes are assembled in this inner felly member with their tenons 3 engaged in the sockets 6 formed in the rim member to receive them—see Fig. II.

The distorted rim member 4 with the assembled spokes therein is then returned or, if necessary, forced into the plane of the spokes in the wheel which brings the spokes into their alined position and it will be 85 found that they are also subjected to a considerable stress if made of the proper dimensions.

The outer felly member 7 is then arranged over the inner member, the outer 90 felly member illustrated being provided with flanges 8 and 9. The flange 9 is then turned down by spinning or rolling after the outer felly member is arranged upon the inner.

With the outer and inner felly members thus assembled upon the set of spokes the assembled parts are arranged in an upsetting machine designated generally by the numeral 10, the machine illustrated in Fig. 100 VII being of the hydraulic type. It is deemed unnecessary to describe in detail the mechanism of this upsetting machine.

The assembled parts are upset by the upsetting machine to compress the spokes and 105 size the wheel, the felly members being of such material and weight as to retain their upset form holding the spokes with the desired pressure at the arch. The wheel is then adapted to receive the tire or head 110

either mounted directly upon the felly member 7 or held in a rim, as 11. A rubber tire 12 is shown conventionally.

5 Wheels may be very rapidly and economically manufactured by my improved method and the wheels so manufactured are of great strength and durability.

The distortion of the inner rim to receive the spokes may be very considerably varied 10 from that shown and my improved method carried out with advantage. However, the particular manner of distorting the rim member is preferred by me at this time and therefore I have illustrated that form.

15 Having thus described my invention, what I claim as new and desire to secure by Letters Patent, is:

The method of making wheels which consists in assembling a set of spokes having

tenoned outer ends and inwardly tapered 20 complementary inner ends in a split inner felly member, the ends of which are distorted laterally from the plane of the spokes in the wheel, bringing said rim member and the spokes so assembled therein into the 25 plane of the spokes in the wheel, arranging a continuous outer metal felly member upon said inner felly member, and upsetting such assembled felly members and spokes to compress the spokes and size the wheel. 30

In witness whereof I have hereunto set my hand and seal in the presence of two witnesses.

G. S. PORTER. [L. S.]
